UNITED STATES PATENT OFFICE

2,497,884

INCLINED CURRENT FLUID SUSPENSION
ORE SEPARATOR

Benjamine F. Hearn, Jackson, Miss., assignor, by direct and mesne assignments, of twenty per cent to Rowe S. Crowder, Jackson, Miss., thirty-seven per cent to Harry J. Valentine, Sr., Phoenix, Ariz., and five per cent to Rufus Creekmore, Jackson, Miss.

Application May 17, 1946, Serial No. 670,443

2 Claims. (Cl. 209—137)

1

This invention relates to devices for the separation of metals from sand, earth and other materials.

An object of the invention is to provide means for separating metals from sand, earth or other materials efficiently and at low cost.

Another object of the invention is to provide means whereby the separation of metals from sand, earth or other materials is accomplished under the influence of a vacuum whereby the lighter sand, earth or other material is separated leaving the metal.

A further object of the invention is to provide a metal separator wherein the sand, earth or other material containing the metal is dumped into a hopper and allowed to pass through a vacuum trap which separates the lighter material from the metal, which then flows or drops into a recovery container or chamber.

Another object of my invention is to provide a receiving hopper for a vacuum metal separator which is adjustable to any desired precision to take care of any grade of material.

Other objects and advantages of my invention will become apparent from the following description of a preferred embodiment thereof as illustrated in the accompanying drawings, and in which,

Figure 1 is a view in sectional elevation of the main portion of my metal separator in which the actual separation of the metal takes place.

Figure 2 is a side elevation of the complete machine including the frame, metal separators, filters, fan and driving mechanism, and

Figure 3 is an end elevation of the device shown in Figure 7.

Like reference characters denote similar parts throughout the several views.

The ore-separating device of this invention includes a frame 5 having a base 6 with posts 7 at the corners and horizontal members 8 and 9 with diagonal braces 10 at the top.

There are also intermediate transverse bars 12 and intermediate longitudinal bars 14, with uprights 16 supporting the longitudinal bars 14, and crossed braces 18. Inclined rails 20 extend longitudinally from the front 22 of the frame to the rear 24, their rearward ends being lower than their front ends. A screening rack 26 is hung from the rails 20 by means of hangers 28 which are pivoted at their upper and lower ends to the rails 20 and the rack 26 respectively, so that the rack 26 remains substantially parallel to the rails 20 while it swings therefrom, the rearward end 30 of the rack 26 being lower than

2

its forward end 32 which protrudes forwardly out of the frame as shown in Figure 2.

The screen 26 is formed with a number of screen sections 27 and these are rocked by an eccentric 34 which is rotatably supported in the frame and connected to the screen frame 26 by connecting rods 36. The agitator pulley wheel 34 is driven by a motor 40 acting through two belts 42 and 44 and an intermediate pulley wheel 46 also supported on the frame.

As the particles are screened through the mesh screen sections, they fall into the upwardly open mouths 48 of receiving hoppers 50 of metal separators 52 which are arranged in pairs in rows 15 extending longitudinally of the frame beneath the screens, so that the hoppers at the extreme left of Figure 2 receive the finest particles and those at the right of the view receive the coarsest particles, and those in between, receiving particles graduated according to their relative position along the frame.

Reference may now be made to Figure 1 for the details of construction of the metal separators. As shown, each metal separator has a receiving hopper 50 through the mouth 48 of which the particles of material to be separated are received. The sides of the receiving hopper converge downwardly to location 54 and then diverge to form a skirt 53 from location 54 to location 56, the lower edge 56 being suitably rounded or smoothed as shown. There is an upper hollow separating cone 58 concentric with the receiving hopper and having its lower marginal edge portion 60 substantially parallel with the surface 35 of the skirt 53, the apex 62 of the upper cone being secured to a hollow cylindrical extension or sleeve 64 which extends upwards through an aperture 66 in a support comprising cross rods 68 which are supported at their ends 70 by being welded to the inner surface of the upper hopper 50 as shown in Figure 1.

The upper end of the extension 64 is threaded into a hollow nut or dust cover member and support 72 which rests upon the portions of cross rods 68 surrounding the aperture 66. It is thus apparent that turning the dust cover 72 will cause the cylindrical extension 64 and hence the upper cone 58 to be elevated or lowered depending upon the direction of rotation of cover 72.

An inner inverted frustoconical chute member 74 is supported on rods 76 secured at their lower ends 78 to the inner surface of the chute member 74 and at their upper ends 80 to an upwardly extending support rod 82 which extends upwardly through the tubular extension mem-

ber 64 and into the recess in the dust cover member 72, with a nut 84 threaded onto its upper end, the nut resting on the upper end of the tubular extension 64, whereby the chute 74 may be raised or lowered by turning the nut 84, or the upper cone 58 and the chute 74 may be raised or lowered together by turning the dust cover member 72. If desired, the dust cover 72 may have a removable cap to afford access to the nut 84.

The chute member 74 has a frusto-conical skirt 86 which is substantially parallel to the conical surfaces 53 and 60, the surfaces 53, 60, and 86 being normally spaced slightly as shown. Adjustable stops comprising wing screws 88 and 90 are disposed in pairs around the skirt 53, extending threadedly therethrough as shown, with the lower ends of the screws 90 bearing against surface 60 on the upper cone 58, and the lower ends of screws 88 bearing against skirt 86 on chute member 74. It is apparent that the screws 90 serve to adjust the spacing between members 53 and 60, and that the screws 88 serve to limit movement adjusting the spacing between members 86 and 60 and hence also between members 86, and 53.

If desired, the upper cone 58 and the chute member 74 may have added support by means of threaded rods 91 extending through and secured to upper cone 58, the lower ends of the rods 91 extending through chute member 74 and having wing nuts 92 bearing against cross piece 94 to support the chute member 74. The upper ends of the rods 91 extend through brackets 96 carried by receiving hopper 50, with wing nuts 98 providing a means of adjustment of the elevation of the upper cone 58 and the discharge chute member 74, whereby the clearances between the surfaces 53, 60 and 86 may also be adjusted.

A lower frusto-conical discharge hopper 100 is supported in any suitable manner in the frame, and has its sides diverging upwards to location 102, there being an upstanding skirt 104 from location 102 upwards as shown, a slide plate 106 being secured to the skirt 104 by means of thumb screws 108 having jam nuts 110 threaded thereon. The lower discharge outlet 112 of the discharge hopper 100 has threads thereon for the reception of a receptacle 114 into which the separated metal particles such as gold, silver, and other metals may fall and be recovered by unscrewing the receptacle 114. The latter may conveniently be a fruit jar of the type commonly in use.

A vacuum pipe 116 extends through an opening 118 into the interior of discharge hopper 100 being supported therein by bracket 119, and having its end 120 tightly fastened over the discharge outlet 122 of the discharge chute member 74. The other end of the vacuum pipe 116 leads to a header 124 shown in Figure 3, which leads to a vacuum pump 126 driven by means of a power belt (not shown) engaging pulley 128. It is thus apparent that when suction is applied in vacuum pipe 116, a vacuum pocket is formed in the chamber 130 into which air is drawn along the paths indicated by the arrows 132 into the vacuum pocket 130, the air traveling at relatively high velocity through the restricted passageways shown. When matter containing metals to be separated is dropped from the screens on the screen rack into the receiving hoppers 50, it passes down along the outer surface of the upper cone 58 and enters the restricted passageways in the direction indicated by the arrows 134, passing between the members 53 and 60, and as it reaches the lower edge of the member 60 as shown in Figure 1, it

is met by the rapidly moving air passing across its path and up between members 60 and 86, with the result that the air 132 forces the lighter particles of material such as sand, dirt and the like upwards along the path of the arrows 132 between members 60 and 86, and into the vacuum pocket 130 whence it drops down into chute 74 and is sucked out through suction pipe 116. At the same time, the weight of the metal particles such as gold, silver and the like is so much greater than that of the sand and dirt particles, that the air 132 which is sufficiently strong to lift the sand and other dirt particles into the vacuum pocket, has no lifting effect on the metal particles and they drop down into discharge hopper 100 and into the fruit jar receptacles 114.

In one preferred example of my device, the slope or pitch of the members 86, 60 and 53 is 45 degrees from the horizontal. The clearance between these members can be adjusted to accommodate any size metal and sand particles from $1/100$ to $1/8$, and the degree of vacuum may be adjusted by means of a damper in the vacuum pipe or other suitable means. In each pair of separators, the spacing between the members 86, 60 and 53, will be adjusted to the size of particles being handled, as will the degree of vacuum.

Although I have described a preferred embodiment of my invention in specific terms, it is to be understood that various changes may be made in size, shape, materials and arrangement without departing from the spirit and scope of the invention as claimed.

I claim:

1. In an ore separator, including a receiving hopper having downwardly-converging sides terminating in an outwardly-flared frusto-conical skirt, a hollow cone including an apex disposed axially of said receiving hopper with base portions thereof underlying said skirt to provide a frusto-conical passage therebetween, a frusto-conical member underlying said base portions of said cone and providing a second frusto-conical passage therebetween, and means for creating upwardly-directed suction in said second passage; the improvement comprising a support, means mounting said support in said receiving hopper above said cone, said support being formed with a vertically-disposed aperture therethrough axially of said receiving hopper, said apex of said cone having an upwardly-extending sleeve slidable in said aperture, the upper end of said sleeve being exteriorly threaded, a hollow nut threadedly engaging said sleeve and bearing on said support to comprise means for adjusting said cone vertically to vary the size of said first passage, a rod slidable in said sleeve, means connecting said rod to said frusto-conical member, the upper end of said rod being exteriorly threaded, a second nut threaded on said rod and bearing on the upper end of said sleeve inwardly of said hollow nut, and said rod and second nut comprising means for independently adjusting said frusto-conical member vertically to vary the size of said second passage.

2. In an ore separator, including a receiving hopper having downwardly-converging sides terminating in an outwardly-flared frusto-conical skirt, a hollow cone including an apex disposed axially of said receiving hopper with base portions thereof underlying said skirt to provide a frusto-conical passage therebetween, a frusto-conical member underlying said base portions of said cone and providing a second frusto-conical passage therebetween, and means for

creating upwardly-directed suction in said second passage; the improvement comprising a support, means mounting said support in said receiving hopper above said cone, said support being formed with a vertically-disposed aperture therethrough axially of said receiving hopper, said apex of said cone having an upwardly-extending sleeve slidable in said aperture, the upper end of said sleeve being exteriorly threaded, a hollow nut threadedly engaging said sleeve and bearing on said support to comprise means for adjusting said cone vertically to vary the size of said first passage, a rod slidable in said sleeve, means connecting said rod to said frusto-conical member, the upper end of said rod being exteriorly threaded, a second nut threaded on said rod and bearing on the upper end of said sleeve inwardly of said hollow nut, said rod and second nut comprising means for independently adjusting said frusto-conical member vertically to vary the size of said second passage, separate adjustable stops carried by said skirt and engaging respectively said base portions of said cone and

said frusto-conical member, said stops being independently adjustable to independently limit adjusting movement of said cone and frusto-conical member in directions to reduce the size of said first and second passages.
